UNITED STATES PATENT OFFICE.

HARRY A. COFFIN, OF MALDEN, MASSACHUSETTS.

OUTLET-BOX.

No. 901,593.

Specification of Letters Patent.

Patented Oct. 20, 1908.

Application filed January 12, 1907. Serial No. 352,009.

To all whom it may concern:

Be it known that I, HARRY A. COFFIN, citizen of the United States, residing at Malden, in the county of Middlesex and State of Massachusetts, have invented certain new and useful Improvements in Outlet-Boxes, of which the following is a specification.

My invention relates to the art of electric wiring and has special reference to what is technically termed knob and tube work.

The particular device which embodies my improvements consists of an outlet box, preferably constructed of iron, through which the main wires pass, and which is also adapted for combination work, *i. e.*, for the transmission of a gas pipe and electric cables through the same device. Such boxes are known in the art but require to be made in a variety of forms to suit various kinds of work, thus new work, old work, straight electric and combination require at least four shapes to adapt them to the requirements of each class of work.

The paramount object of my invention is to so design an outlet box for electric wiring that it may be readily adapted to the different conditions, thus promoting economy in the manufacture and saving time in constructive work.

Another object of my invention is to produce an outlet box for the purpose stated that will be simple in construction and that can be produced at a minimum cost by providing means for compensating for lack of uniformity in the castings.

I accomplish the above and other minor objects by the use of the device illustrated in the accompanying drawing which forms a part of this specification and in which:—

Figure 1 is a front elevation of my improved outlet box for electric wiring; Fig. 2 is a sectional view on the line 2—2 of Fig. 1; Fig. 3 is a transverse section showing a modified form of diaphragm and bushing; Fig. 4 is a transverse section of the form seen in Figs. 1 and 2 showing the method of applying a cover to the box, and Fig. 5 is a front elevation of a modification of the ring casing.

Referring to the drawing, 6 indicates a ring shaped casing or rim provided with an inwardly projecting flange 7 which forms a ledge upon which rests a diaphragm 8 furnished with a central aperture 8^a, surrounding which is a flange 9 having internal threads 10. The diaphragm or plate 8 is

provided with a plurality of circular openings 11, for the passage of flexible conduits. Countersunk screw holes 12 are formed in the said plate by means of which the box 60 may be secured in the desired location. A reduction bushing 13 having a projecting flange 14 is furnished with external threads to engage the internal threads 10 of the flange 9 the said flange 9 engaging the flange 65 on the bushing to limit its vertical movement. The said bushing has a central bore 15 provided with internal threads 16. These threads may be cut to a standard size to engage similar threads cut upon a gas pipe 70 when the combination system is employed.

In some cases it may be desirable to close the box with a cover 17 which has a depressed center 18 and a central opening 19 through which the body of the reduction 75 bushing is passed and screwed down until the center 18 of the cover is held firmly between the flange 14 of the bushing and the upper margin of the flange or collar 9, the periphery of the said cover resting upon the 80 free margin of the ring 6.

In Fig. 3 is shown a modified form of reduction bushing and plate. In this case the collar 9 is omitted and the central portion of the plate 8 formed with an offset 20 the 85 threads of the central aperture 8^a being omitted. The modified form of bushing 21 is similar to the bushing shown in Figs. 2 and 4 with the exception that the external threads are omitted, the outside being 90 smooth and adapted to fit the opening 8^a of the plate 8. The flange 22 is received in the depression in the plate 8 formed by the offset 20, so that the free surface of said flange is flush with the corresponding surface of 95 the plate 8. The bushing will be thus held securely in place and the flange will not interfere with the use of the device for old work.

It is desirable for convenience in handling that the plate 8 and rim 6 should have a firm frictional contact so that they will not become separated with ordinary usage. As this will require some nicety of fitting, especially when the parts are made of cast iron, in order to enable the parts in question to be assembled without preliminary finishing and thus promote economy in the manufacture, I provide a modified form of rim shown in Fig. 5. The part is in the shape of an open or expansion ring, the ends being 105 beveled to form a diagonal juncture 23, and

thus allow the ring to spread or contract to suit slight variations in the diameter of the plate 8.

The method of employing my improved outlet box for various kinds of work is as follows:—For new work the box is to be used in the complete form as shown in Figs. 1, 2, and 4. For old work the outer rim or shell 6 is knocked off. For combination work the reduction bushing is removed, and for straight electric the bushing is inserted to receive a nipple from which the fixture is suspended.

Having thus described my invention what I claim as new and desire to secure by Letters Patent, is:—

1. An outlet box comprising a plate having a threaded central opening and provided with apertures to receive wires and other apertures to receive attaching devices, a rim loosely surrounding and supporting said plate, a bushing having a threaded engage-

ment with the central opening of said plate, and means on said plate for limiting the vertical movement of said bushing in one direction.

2. An outlet box comprising a plate having a threaded central opening and provided with apertures to receive wires, a rim loosely surrounding said plate and provided with a flange to receive the plate, a bushing having a threaded engagement with the central opening of said plate, and provided with a flange, and a cover plate having a central opening to receive said bushing, said cover plate being arranged between said bushing flange and the first named plate, for the purpose set forth.

In testimony whereof I affix my signature in presence of two witnesses.

HARRY A. COFFIN.
